UNITED STATES PATENT OFFICE.

HARRY MINTZ, OF MATTAPAN, MASSACHUSETTS.

HAMMOCK.

1,387,801.

Specification of Letters Patent. Patented Aug. 16, 1921.

Application filed October 8, 1920. Serial No. 415,542.

To all whom it may concern:

Be it known that I, HARRY MINTZ, citizen of the United States, and resident of Mattapan, in the county of Suffolk and State of 5 Massachusetts, have invented new and useful Improvements in Hammocks, of which the following is a specification.

This invention relates to hammocks and more particularly to that type commonly 10 known as couch hammocks and which according to the usual construction comprise essentially a cushioned seat or frame having its ends supported by flexible suspension members.

15 In hammocks of this type the flexible end suspension members which usually consist of strips of textile fabric such as canvas or the like, are suitably connected at their upper ends to rigid bars, to which are attached chains or other means by which the hammock is suspended from an elevated support. To the lower edges of these fabric strips the hammock frame is commonly directly attached. As usually constructed the 20 rigid supporting bars are substantially straight from end to end. When the hammock frame is subjected to load, as by the seating of a person therein, it is found usually that it sags slightly in a front to rear direction, whereby the load, which theoretically is carried in a uniform manner by the textile end suspension member is brought to bear upon the latter adjacent the central portion thereof alone. This causes excessive 25 strain upon the central portion of the textile material, occasioning rapid wear and failure of the same.

An object of the present invention is to 30 so arrange the various parts as to provide for substantially uniform distribution of the load strain over the entire area of the suspension strip. To this end it is proposed to form the rigid bar upon which such strip is mounted with a curved upper surface the 35 curvature of which will be determined in such a manner as to provide for substantial uniform distribution of the strain upon the fabric throughout the front to rear extent of the same even though the load be applied 40 in a nonuniform manner to the lower edge of such strip. While a curve such as to produce desired results may vary somewhat in accordance with the dimensions of the parts of the materials employed, it appears 45 probable that such a curve should approach

that known mathematically as a catenary, that is, to say the curve assumed by a theoretically perfectly flexible and weightless cord when suspended by its ends between two supports.

60 In hammocks of the above type as commonly constructed and as herein above referred to, the end supporting bars are commonly formed with a substantially straight or flat upper surface. The bars as thus formed are found to be very uncomfortable as arm rests when so employed by the user of the hammock, and it is desirable to arrange an end bar so that its upper surface may conform 65 to the contour of the forearm of the user of the hammock, thus rendering the same more suitable as an arm rest. This may be accomplished in substantially the same manner as is the object above, it being found that the curvature of the upper surface of the bar 70 such as to provide the uniform tension desirable in the flexible end suspension member, sufficiently approximates the contour of the human arm as to make the bar so constructed acceptable as an arm rest.

80 Hammocks of this type as commonly constructed have the flexible end supporting member supported upon the end suspension bars by the provision of an elongated pocket or hem in the upper edge of the flexible 85 member, such pocket or hem serving to receive and inclose the bar. It is desirable however, to have the ends of the bar inclosed as well as the side portions thereof, and further that such end closing means appear 90 substantially like that of the material forming the pocket.

An object of the present invention is to provide for concealing the ends of the bar exposed by the open ends of the pocket, such 95 closing means being of a simple character readily constructed and such as will not detract from the appearance of the hammock.

To this end it is proposed to provide caps of a fabric similar to that employed for the 100 end suspension members and to slip such caps over the ends of the supporting bars, the edges of the caps lying beneath the ends of the pockets in the suspension members and being secured in any desirable manner there- 105 to or to the end bars.

As a convenient mode of carrying into effect the above objects, the arrangement disclosed in the accompanying drawings may be employed, it being understood however, 110

that this is merely illustrative of one of the many ways in which such objects may be accomplished.

In the accompanying drawings Figure 1 is an end elevation of a hammock embodying the present invention, parts being broken away for clearness of illustration, and

Fig. 2 is a detail to enlarged scale, illustrating the end of one of the supporting bars and the manner of covering the same.

1 indicates the frame which may as usual be of angle iron or other suitable stiff and relatively light material. Upon this frame is supported the mattress 2 and rising from 15 the frame at each end are lugs 3 to which may be connected links as 4, 5, serving to support a back frame 6 carrying the back cushion 7. The structure thus far described is substantially in accordance with that dis- 20 closed in the patent to Mintz, 1,308,096 filed July 1, 1919, although the exact arrangement and construction of the frame and back rest is not essential to the carrying into effect of the present invention.

25 The end members of the frame 1 are supported in the usual manner by means of flexible strips of material preferably of textile fabric such as indicated at 8. These textile strips having the frame suspended at 30 their lower edges are supported at their upper edges upon rigid supporting bars such as indicated at 9. The bars 9 may have staples or eyes 10, 11, secured thereto, to which the ends of chains 12, 13 may be at- 35 tached, the upper ends of these chains being fastened to a ring 14 or other suitable device. For supporting the adjustable back rest in position a chain 15 may be employed as in the patent above referred to.

40 In order to compensate for the irregular strains which may be imposed upon the fabric strips due to the springing of the frame 1 when loaded, the upper surfaces of the bars 9 are provided with a downwardly con- 45 cave curvature as indicated at 16. The curvature of the upper surface of the bar will preferably take the form of a catenary or of a curve of generally similar type, it being found that a curve of this form is espe- 50 cially well adapted to distribute the strains uniformly throughout the length of the fab- ric when the latter is subjected to a centrally disposed load such as is imposed thereupon when a person reclines in the hammock.

55 While a curve of this type is particularly desirable, it is not to be understood that curves of other forms may not be employed, as any curvature of the upper surface of the bar, such as to assist in distributing the strains 60 upon the fabric may, it is contemplated, be employed without departing from the spirit of the present invention.

From the foregoing it will be evident that the vertical distances between the ends of frame 1 and the top bars 9 are reduced

throughout the central regions of the ends by curving said bars downwardly throughout their central portions, thereby reducing the vertical dimensions of the fabric ends 8 in the middle. Inasmuch as the middle 70 portions of the ends 8 will stretch less by virtue of their reduced dimensions the end bars of frame 1 will sag less in the middle. This is advantageous not only for mechanical reasons but also because the fabric ends 75 8 are subjected to less oblique strains and therefore present a smoother appearance than when the ends of frame 1 sag in the middle.

While the upper surface of the bar need 80 not necessarily be parallel to the lower surface thereof, it is found convenient in practice to make the bar of substantially uniform cross section from end to end, the lower surface thereof between points such as 17, 18, 85 adjacent the ends of the bar, being curved downwardly as indicated at 19 and lying substantially parallel to the upper surface thereof. As a convenient mode of securing the fabric strips to the bar, the fabric strip 90 may be provided with a longitudinally extending pocket at 20, such pocket taking the form of a hem formed by turning the edge of the fabric over and uniting the edge to the main body of the fabric by lines of 95 stitches as indicated at 21. Other modes of securing the fabric to the bar may, however, be employed if desired, such for example as by the use of metallic fasteners or clamping devices.

When, as herein shown, the bar is of substantial cross section, it is particularly desirable that the end of the pocket be provided with some means for covering and concealing the end of the bar. Such means 100 may, if desired, take the form of a cap 22, preferably of textile fabric of a similar texture and color to that employed for the fabric supporting strip 8. Such cap may be produced by folding the fabric as indicated 110 at 23 and the cap thus formed will be slipped over the end of the bar with its free edges underlying the end portion of the pocket, and secured in any desired manner thus, fully concealing the end of the bar from 115 view.

Having thus described a preferred form of the invention and the mode of employment of the same, what I claim and desire to secure by Letters Patent of the United 120 States is:

1. A hammock of the class described comprising a seat frame and an end bar, a strip of fabric secured to said frame at the bottom and to said bar at the top, and said bar 125 having a downwardly curved central portion whereby the vertical dimension of said fabric is greater at the ends than at the central portion.

2. A hammock of the class described com- 130

prising a seat frame and an end bar, a strip of fabric secured to said frame at the bottom, and having at its top a pocket adapted to receive said bar, and said bar having a 5 downwardly curved central portion whereby the vertical dimension of said fabric is greater at the ends than at the central portion.

3. A hammock of the class described comprising a seat frame and an end bar, a strip of fabric secured to said frame at the bottom and to said bar at the top, and said bar having end portions substantially parallel with said frame, and a downwardly curved 15 central portion whereby the vertical dimension of said fabric is greater at the ends than at the central portion.

4. A hammock of the class described comprising a seat frame and an end bar, suspension means secured to said bar adjacent 20

the ends thereof whereby the central portion of said bar is unobstructed, a strip of fabric secured to said seat frame at the bottom and to said bar at the top, and said bar having a downwardly curved central portion whereby the vertical dimension of said fabric is greater at its ends than at the central portion. 25

5. In a hammock device in combination with a supporting bar, a fabric strip having a longitudinal open ended pocket within which said bar is inclosed, and a fabric cap having an open end, said cap being constructed and arranged to be slipped over an end of said bar and to have its free edges concealed 30 from view by the end portion of said pocket. 35

Signed by me at Boston, Massachusetts this 6th day of October 1920.

HARRY MINTZ.
